UNITED STATES PATENT OFFICE.

ROBERT E. L. PARNELL, OF GAINESVILLE, GEORGIA.

WINDOW-SCREEN.

933,782.

Specification of Letters Patent. Patented Sept. 14, 1909.

Application filed March 29, 1909. Serial No. 486,420.

To all whom it may concern:

Be it known that I, ROBERT E. L. PARNELL, a citizen of the United States, residing at Gainesville, in the county of Hall and State 5 of Georgia, have invented a new and useful Window-Screen, of which the following is a specification.

The objects of the invention are, generally, the provision in a merchantable form, of a 10 device of the class above described which shall be inexpensive to manufacture, facile in operation and devoid of complicated parts; specifically, the provision of a frame, and a screen designed to be assembled with the 15 frame in such a manner that the said screen may yield when the parts of the frame are moved pivotally upon each other; the provision in a novel and improved form, of resilient means for maintaining the screen 20 construction normally in alinement; other and further objects being made manifest hereinafter, as the description of the invention progresses.

The invention consists in the novel construction and arrangement of parts hereinafter described, delineated in the accompanying drawings, and particularly pointed out in that portion of this instrument wherein patentable novelty is claimed for certain 25 distinctive and peculiar features of the device, it being understood, that, within the scope of what hereinafter is thus claimed, divers changes in the form, proportion, size and minor details of the structure may be 30 made without departing from the spirit or sacrificing any of the advantages of the invention.

Similar numerals of reference are employed to denote corresponding parts 35 throughout the several figures of the drawings.

In the accompanying drawings, Figure 1 shows my invention in perspective; and Fig. 2 is a transverse section thereof, the 40 device being mounted in a window casing.

In carrying out my invention I provide primarily a frame comprising a pair of open sections 1. The adjacent ends of the sections 1 carry plates 2 which are upbent at 45 their extremities to form overlapping ears 3 in which is mounted a pintle 4.

Disposed between the ears 3 and about the pintle 4 is a spring 5, the ends 6 of which bear upon opposite plates 2.

Disposed upon the faces of the sections 1 50 is a screen 7 held in place by binding strips

8 which are rigidly assembled with the sections 1, each of the said binding strips 8 terminating adjacent the pivotal connection between the sections 1. The adjacent ends 9 60 of the binding strips are carried inward upon the plates 2, each of the ends 9 serving to aid screws 18 or like elements in holding the plates 2 upon the sections 1. The adjacent ends 9 of the binding strips are cut away 65 upon their edges, to free a portion of the edge of the screen and to form a shoulder 10 to engage the edge of the screen. By this construction a portion 11 of the screen is left free at its edge and unattached to the 70 sections 1. By thus leaving a portion of the edge of the screen 7, adjacent the pivotal connection between the sections, free, the said screen will spring away from the faces of the sections 1 when the frame is bent as 75 shown in dotted lines in Fig. 1. By this construction the screen is not strained or creased, and the screen is further protected, and its life is materially lengthened by the fact that, as shown in Fig. 2, the screen 80 is transversely bulged in line with the hinge connection between the sections 1, as denoted by the numeral 12.

In Fig. 2 the numeral 15 denotes the casing of a window, the numeral 16 denoting the 85 lower sash. When it is desired to mount the device of my invention in the top of the window frame, the outer sash may be pushed downward, the screen being inserted above the upper sash when in its depressed or 90 lowered position. In order that my device may readily be used under such circumstances I groove the remote edges of the sections 1 as denoted by the numeral 14, in order to receive the sash cord 17 whereby the 95 upper sash is suspended.

The device may readily be folded partially in order that its remote edges may be inserted into the casing of the window, and when the sections 2 are released, the spring 100 5 will cause them to assume positions substantially in alinement with each other, the device automatically assuming the position shown in Fig. 2.

Having thus described my invention what 105 I claim as new and desire to protect by Letters Patent is:—

1. In a device of the class described, an open frame comprising separate sections arranged to be brought into alinement a hinge 110 uniting the sections and having its pivot member spaced from the frame, and a screen

mounted upon the sections; a portion of the screen adjacent the hinge union between the sections being unattached to the sections, and being bulged transversely of the screen
5 when the sections are in alinement.

2. In a device of the class described, an open frame comprising separate sections arranged to be brought into alinement a hinge uniting the sections and having its pivot
10 member spaced from the frame; and a screen mounted upon the sections; a portion of the screen adjacent the hinged union between the sections, being bulged transversely of the screen when the sections are in alinement.

15 3. A device of the class described comprising a pair of separate sections arranged to be brought into alinement; hinges uniting the sections and having their pivot members

spaced from the sections; a binding strip 20 mounted on each section and arranged to extend upon a hinge; a screen disposed between the binding strips and the sections, the strips at their adjacent ends being cut away in their edges, to free a portion of the 25 edge of the screen, and to form a shoulder to engage the edge of the screen, the screen being bulged transversely in alinement with the free portions of the edges thereof when the sections are in alinement.

30 In testimony that I claim the foregoing as my own, I have hereto affixed my signature in the presence of two witnesses.

ROBERT E. L. PARNELL.
